UNITED STATES PATENT OFFICE.

CHARLES C. TOZIER, OF CHELSEA, ASSIGNOR, BY DIRECT AND MESNE ASSIGNMENTS, TO WALTER J. PAIN, OF BOSTON, MASSACHUSETTS.

BRIDGE-GUARD.

SPECIFICATION forming part of Letters Patent No. 374,882, dated December 13, 1887.

Application filed August 18, 1887. Serial No. 247,316. (No model.)

To all whom it may concern:

Be it known that I, CHARLES C. TOZIER, of Chelsea, in the county of Suffolk, State of Massachusetts, have invented a certain new and useful Improvement in Bridge-Guards, of which the following is a description sufficiently full, clear, and exact to enable any person skilled in the art or science to which said invention appertains to make and use 5 the same, reference being had to the accompanying drawings, forming part of this specification, in which—

Figure 1 is a top plan view of a bridge provided with my improvement; Fig. 2, a side elevation of the same as viewed from the line X X in Fig. 1, some of the parts being shown in section; Fig. 3, a vertical section taken on the line Y Y in Fig. 2, certain parts being shown in side elevation; Fig. 4, a view showing one of the springs and the ratchet mechanism, and Fig. 5 a top plan view of one of the springs detached.

Like letters of reference indicate corresponding parts in the different figures of the drawings.

My invention relates to means for preventing accidents to brakemen when riding on the top of freight-cars by being brought into contact with overhead bridges; and it consists in 30 a novel construction and arrangement of parts, as hereinafter more fully set forth and claimed, the object being to produce a more effective and otherwise desirable article of this character than is now in ordinary use.

The nature and operation of the improvement will be readily understood by all conversant with such matters from the following explanation.

In the drawings, A B represent the tracks 40 of the railroad, C the train of cars, and D an elevated bridge resting on abutments E and spanning the road-bed in the usual manner.

Projecting horizontally from one of the sills or side timbers of the bridge over the track B 45 there are two brackets, d, and journaled horizontally in the said brackets there is a shaft, m, provided at one of its ends with a ratchet-wheel, b, with which a retaining-pawl, i, pivoted on one of said brackets, engages.

Secured centrally and longitudinally beneath the bridge D there is a timber, f, to

which is attached a series of elliptic springs, g, as best shown in Fig. 4. The upper member of each of said springs is divided, and the inner ends of each section elongated to 55 overlap the other, being provided with slots t, through which the attaching-bolt v passes loosely, this construction and arrangement of the parts enabling the ends of the sections at the bolt v to slide on each other as the spring 60 is compressed and rendering the spring more elastic than it would otherwise be. I do not, however, confine myself to springs of any special construction, as any suitable springs adapted to perform the same functions may 65 be employed. The springs shown in the present instance are connected with each other or “tied” by a transversely-arranged rod, z, which is secured to the lower member of each spring, as best seen in Fig. 4.

Disposed at each side of the road-bed, preferably about one hundred feet from the bridge D, there is a stout post, H, and mounted on said posts there is a strong girder or timber, J, which spans the tracks A B at a height 75 slightly above the floor of the bridge D, or about seven feet above the car standing on the track.

Disposed beneath the bridge D, above the track B, are a series of guard-wires, K, resting against the lower side of the rod z, and being secured at one end to said girder and at the other to the shaft m.

The above description applies more especially to the track B; but the track A is provided with a series of guard-wires in substantially the same manner, which project from the bridge D in the opposite direction, as shown in Fig. 1, to provide for trains running in opposite directions.

When the road has but one track, two sets of the guard-wires K are employed, and arranged so as to extend over the tracks to the girders J at each side of the bridge, it being understood, of course, that in such a case 95 either one or two rods m may be employed—one on each side of the bridge—although but one set of springs, g, are necessary.

The use of my improvement is illustrated in Fig. 3, in which the cars C are represented as approaching the bridge D on the track B in the direction indicated by the arrow for

said track in Fig. 1, and when the brakeman N on the rear car passes under the girder J, if he has not already stooped sufficiently to pass beneath the bridge D, he will be struck 5 by the guard-wires K and forced downward a sufficient distance to enable him to pass beneath the bridge without injury, and in a manner which will be readily understood without a more explicit description.

10 The springs g cushion the guard-wires, being designed to yield sufficiently when the brakeman strikes them to prevent all injury from the shock occasioned thereby, any desired degree of tension being placed on said wires by means of the ratchet mechanism on the rod m.

I do not confine myself to securing the inner ends of the wires directly to the bridge, as it will be obvious that they may be attached 20 to any suitable support under or near the bridge, provided the outer ends are elevated above the inner ends and secured at a proper distance from the bridge, substantially as described. Neither do I confine myself to the 25 use of springs for cushioning the wires; nor to the ratchet mechanism for exerting a tension thereon, as these may be dispensed with, if desired; nor to placing the tension-shaft m on the bridge D, as it may be disposed at the 30 outer ends of the wires K, and supported by the posts H, if desired, the inner ends of said wires being secured directly to the bridge, or to a support beneath or near the same.

When the road-bed is provided with but 35 one track, the guard-wires are preferably cut long enough to extend between the girders J, beneath the rod z, and a tension-shaft, m, provided at each end of the wires, said shafts being mounted on the girders, or journaled in boxes 40 on the posts H, as preferred, the springs g and rod z being used beneath the bridge, substantially as shown.

Having thus explained my invention, what I claim is—

45 1. In a device of the character described, the combination of a railway-track, a bridge

disposed above said track, a series of guard-wires, and supports for said wires, the wires extending from one side of the bridge outwardly along and over the track, and having 50 their outer ends elevated above the plane of their inner ends, or above their lowest point at or near the bridge, substantially as specified.

2. In a device of the character described, 55 the combination of a railway-track, a bridge disposed above said track, a series of guard-wires, and supports and tension mechanism for said wires, the wires extending from one side of the bridge outwardly along and over 60 the track, and having their outer ends elevated above the plane of their inner ends, or above their lowest point at or near the bridge, substantially as specified.

3. In a device of the character described, 65 the combination of a railway-track, a bridge disposed above said track, a series of guard-wires and supports, cushioning-springs, and tension mechanism for said wires, the wires extending from one side of the bridge and outwardly along and over the track, and having 70 their outer ends elevated above the plane of their inner ends, or above their lowest point at or near the bridge, substantially as set forth.

4. In a device of the character described, 75 the combination of the guard-wires K, posts H, girder J, springs g, rod m, and bridge D, arranged to operate substantially as described.

5. In a device of the character described, 80 the combination of the guard-wires K, springs g, posts H, girder J, rod m, ratchet-wheel b, pawl i, and bridge D, arranged to operate substantially as specified.

6. In a device of the character described, 85 the springs g, provided with the slots t, in combination with the bolt v, rod z, wires K, and bridge D, substantially as specified.

CHARLES C. TOZIER.
